UNITED STATES PATENT OFFICE.

JOSEPH S. STOGDALE, OF DUNBAR, PENNSYLVANIA, ASSIGNOR OF ONE-HALF TO
JAMES M. RAINES, OF RAINELLE, WEST VIRGINIA.

GRATE.

Application filed February 4, 1924. Serial No. 690,400.

To all whom it may concern:

Be it known that I, JOSEPH S. STOGDALE, a citizen of the United States, and a resident of Dunbar, Fayette County, Pennsylvania, have invented certain new and useful Improvements in Grates, of which the following is a specification.

This invention relates to improvements in grates, and more particularly to grates designed for use in the fire boxes of locomotives, or similar engines; the principal object of the invention being to provide a grate comprising a plurality of parallel, horizontally shiftable fire bars making up its central portion with vertically swinging grates at its ends which provides for an easy removal of clinkers and ashes.

Another object of the invention resides in the provision of fire bars that may be readily removed and replaced when such is desired and which are equipped with interchangeable and removable grate bars.

Another object of the invention resides in the provision of and details of construction of means for shifting the slideable fire bars longitudinally at different times and for moving the pivoted grates into and from alignment with the fire bars.

Other objects reside in the details of construction of the various parts embodied in the invention and in their mode of operation.

In accomplishing these objects I have provided the improved details of construction, the preferred forms of which are illustrated in the accompanying drawings, wherein—

Figure 1 is a vertical, sectional view of a locomotive fire box equipped with a grate that is constructed in accordance with the present invention.

Figure 2 is a plan view of the grate.

Figure 3 is a side view of one of the outside fire bars embodied in the grate showing its actuating cam.

Figure 4 is a longitudinal section of one of the fire bars taken on the line 4—4 in Figure 2 illustrating the disposal of the removable grate bars therein.

Figure 5 is a transverse section taken on the line 5—5 in Figure 2, particularly illustrating the cam shaft and the shifting cams thereon.

Referring more in detail to the drawings—

1 designates what may be the fire box of a locomotive boiler and which comprises opposite side sheets 2 and 3, a front flue sheet

4 and a back wall 5. Supported from the side sheets transversely of the fire box are two parallel grate supporting beams 6 and 7, upon which there is slidably supported a plurality of parallel fire bars 8 which are retained properly in spaced relation within grooves 9 formed in the top edges of the supporting bars. These fire bars are all of the same length, and are provided at their ends with extending fingers 10 adapted, as presently described, to mesh with fingers of grates 12 that are swingingly supported at the opposite ends of the fire box. Two of these latter grates 12, as shown in Figure 2, are mounted at each end of the fire box and are pivotally supported by means of trunnions 13 at their ends upon brackets 14 fixed at opposite sides of the bars and ends of the fire box. These grates are adapted to close the space between the end walls of the fire box and the ends of the bars 8 and are mounted to swing from horizontal position to downwardly inclined positions, and when in the latter position permit the removal of clinkers and ashes from the grate into the ash box.

Each of the grates 12 has fingers 12' extending therefrom and these are adapted to inter-mesh with the fingers of the fire bars, as is shown in Figure 2, to prevent the fire from falling through when the bars 8 are shifted toward one end or the other.

The means provided for moving the pivoted grates comprises the levers 18 that are pivotally mounted on brackets 19 on the outside end, at the back end of the boiler and which are connected at their lower ends with rods or links 19' that extend to and are pivotally connected with depending lugs 20 on the grates. Inward or outward movement of the upper ends of the levers 18 causes the swinging movement of the grates 12, with which they are connected, to horizontal or downwardly inclined positions. Any suitable means could be provided for holding the levers 18 at set or adjusted positions. It is preferred to have the fingers of the bars 8 and grates 12 cast on blocks 20 that may be mounted in dovetailed slots 21 in the bars, or grates, so that should the fingers become burned off or broken, they could be replaced without necessitating the replacing of the grate or the bar.

Each of the fire bars 8 consists of an open frame wherein grate bars 25 are held in par-

allel relation. In the present construction, I have shown eight fire bars. However, it is to be understood that more or less could be used in accordance with the size of the fire box and also that the number of grate bars used would depend upon the size and character of the fire bar. Each of the fire bars in the present construction is equipped with nine grate bars that are placed end to end in three parallel rows. These are supported at their ends in interlocked relation, as shown in Figure 4, from the outer ends of the fire bars from bridge walls 27 therein. Each grate bar is equipped near its ends with laterally extending lugs 28 which engage each other to hold the bars properly in spaced relation and they are all V-shape in cross section so that ashes or cinders will not clog between them.

20 The means which I have provided for shifting the fire bars longitudinally back and forth comprises a cam shaft 35 mounted rotatably in brackets 36 fixed to the opposite walls of the fire box below the grate so that the shaft extends transversely beneath the ends of the bars 8. Centrally of the shaft provision is made by means of the gear 37 whereby the shaft may be revolved from a suitable driving mechanism and keyed on the shaft 35, near its ends, are cams 38 and 38' adapted, as the shaft revolves, to be brought into contact with lugs 39 that depend from the two outside bars of the grate to cause these to be shifted forwardly or toward the flue sheet 4.

25 The intermediate grate bars are shifted forwardly after the advance of the two outside bars by means of a cross bar 40 that is fixed at its end in the two outside bars and which extends through slots 41 in the intermediate bars, as shown in Figure 4; the slots being shorter in length than the distance of movement of the outside bars so that, as the cross bar 40 is carried forwardly by the movement of the two outside grate bars, it will engage with the forward ends of the slots of the intermediate bars to shift them forwardly.

30 There is also provided on the shaft 35, adjacent to the cams 38-38' another set of cams 48-48' that are adapted, as the shaft 35 continues to rotate, to engage with lugs 47 formed on the two outer grate bars in offset relation to the lugs 39 to shift these two outside bars rearwardly or toward the wall sheet 5. It will be stated here that the slots 41 in the intermediate bars through which the bar 40 extends, are so located that this rearward shifting of the two outside bars does not cause movement of the intermediate bars.

35 There is also provided on the shaft 35 beneath the intermediate bars 8, cams 45 which are adapted, as the shaft continues to ro-

tate and after the outside bars 8 have been shifted rearwardly, to engage at different times with cross members 46 on the intermediate bars to shift them rearwardly. By causing the bars to move at different times, a better sifting of the ashes is obtained.

40 This cam shaft may be revolved continuously or when desired, and this effects a shifting of the bars to automatically sift the ashes from the fire. When clinkers or cinders are to be removed, the end grates 12 may be lowered and the cinders raked off into the ash box.

Having thus described my invention, what I claim as new therein and desire to secure by Letters-Patent, is:

1. The combination with a fire box and transversely located grate supporting beams of a grate comprising a plurality of parallel fire bars mounted on the supporting beams for longitudinal shifting, a cam shaft, cams in said shaft for shifting the two outside bars forwardly and rearwardly, means carried by the two outside bars for moving the intermediate bars forwardly after a certain amount of movement of the outside bars and means on the cam shaft for shifting the intermediate bars rearwardly.

2. The combination with a fire box and transversely located grate supporting beams of a grate comprising a plurality of parallel fire bars mounted on the supporting beams for longitudinal shifting, a cam shaft, cams in said shaft for shifting the two outside bars forwardly and rearwardly, means carried by the two outside bars for moving the intermediate bars forwardly after a certain amount of movement of the outside bars and a series of cams on the cam shaft engageable with lugs of the intermediate bars to return them rearward at different times.

3. The combination with a fire box and transversely located grate, supporting beams therein, of a grate comprising a plurality of parallel fire bars mounted on the supporting beams for longitudinal shifting, the said bars that are intermediate the two outside bars having longitudinally extending slots therein, a cross bar fixed at its ends to the two outside fire bars and extended through said slots of the intermediate bars, a rotatable cam shaft mounted transversely beneath the bars, cam engaging means on the fire bars, cams on the cam shaft engageable with the said cam engaging means of the outside bars to move them longitudinally and to effect like movement of the intermediate bars through said cross bar, and other cams on said shaft operable to return the fire bars at different times.

Signed at Dunbar, Fayette County, Pennsylvania this 12th day of January, 1924.

JOSEPH S. STOGDALE,
